T. J. PARKER

AVIATION TOY

Filed Oct. 10, 1923

INVENTOR:
Thomas J. Parker

BY *Allen & Allen*,
ATTORNEYS.

UNITED STATES PATENT OFFICE.

THOMAS J. PARKER, OF CINCINNATI, OHIO, ASSIGNOR OF ONE-HALF TO JOHN G. CYPHERS, OF CINCINNATI, OHIO.

AVIATION TOY.

Application filed October 10, 1923. Serial No. 667,727.

To all whom it may concern:

Be it known that I, THOMAS J. PARKER, a citizen of the United States, and a resident of Cincinnati, in the county of Hamilton and State of Ohio, have invented certain new and useful Improvements in Aviation Toys, of which the following is a full, clear, and exact description, reference being had to the accompanying drawings, forming part of this specification.

My invention relates to toys in which the player can gain experience in the principles of aviation, and in which a miniature aeroplane can be projected through the air by means of a gun.

It is the object of my invention to provide an aeroplane, which has an elevator, rudder and a warping arrangement from the wings, if desired, and which resembles in its actions in the air, a regular sized machine. It is also my object to equip this toy device with a member which can be set into a projecting barrel, and will enable the user to mount the aeroplane in a balanced position in such a barrel and by means of a spring or the like, project the aeroplane in the desired direction and angle of elevation.

These objects and other advantages to be noted, I accomplish by that certain construction and arrangement of parts to be herein-after more specifically pointed out and claimed.

In the drawings:

Figure 1 is a side elevation of a gun for use in my toy, with the barrel thereof in section.

Figure 2 is a plan view of the aeroplane set over the barrel, ready for projection.

Figure 3 is a detail of the rear end of the body of the aeroplane, showing the rudder adjustment.

Figure 4 is a side elevation of the device complete without the gun.

Figure 5 is a front elevation of the device, mounted in the gun, as in Figure 2.

While I have shown a spring projecting device for my toy and shown the projection implement in the shape of a gun, with stock and trigger, it will be understood that some other device of the same function could be provided.

In the form shown in the drawings, the stock 1, is shown as supporting the barrel 2,

which barrel is formed with a lengthwise slot 2^a along the underside thereof.

Within this barrel is a spring 3, which bears against a piston 4, mounted on a rod 5. The spring is held at the rear end by means of a disk 6, through which the rod 5 passes, and this rod is notched at 7, to engage with the latch arm 8 of the trigger 9. The end of the rod protrudes through the rear of the barrel, where it may be equipped with the handle 10, so that when the rod is pulled back until caught by the latch arm, the spring will be compressed, and so that upon pulling on the trigger the rod will be released and the piston 4 will be projected through the path permitted by the handle 10, through the barrel. I use a piston 7^a 70 on the tip of the rod to engage the projectile.

The aeroplane is shown as having a fuselage 11, built to imitate the fuselage of a full sized plane, with the running gear 12, secured thereto. At the rear of the fuselage is the rudder 13, mounted on a vertically placed hinge 14, and having a forwardly projecting tiller 15. This tiller passes over a notched segment 16, so that the movement of the tiller will adjust the rudder, and this adjustment will be held during flight, by means of the engagement of the tiller between the notches.

The elevators 17, are hinged at 18 to the sides of the fuselage onto small plates 19, and have tiller arms 20, which pass over notched segments 21, so that adjustment can be had in the same way as with the rudder and its tiller.

The wings 22, (in this instance a monoplane is shown) are mounted on struts 23, in the usual manner, and wires 24 may be used to hold the tips of the wings in desired relation to the fuselage. A wide variation in wing design is possible as in the usual aeroplane construction.

Set on a pair or more of arms 25, held securely in the fuselage, is a projectile 26, which is made to fit the barrel of the gun. 100 The arms 25 are of a size to fit within the slot 2^a.

Thus the projectile may be inserted within the barrel with the wings above the barrel, and moved back until its rear end lies in the path of the piston on the spring plunger.

er. When this plunger is retracted and then released by the trigger, the projectile and with it the aeroplane will be shot away from the gun and will make a flight through the 5 air.

Due to the location of the projectile beneath the upper wing, and the presence of the slot in the barrel which holds the toy aeroplane in a fixed angular relation to the barrel, a perfect start can be given to the flight, without the projecting apparatus interfering in 10 any way.

I wish to include as within the scope of my invention such mechanical equivalents 15 as will occur to the skilled man in the arts involved.

Having thus described my invention, what I claim as new and desire to secure by Letters Patent, is:—

20 An aviation toy comprising a winged struc-

ture with upwardly extending members supporting a lengthwise member adapted for use as a projectile and for fitting within the barrel of a gun, said barrel with a longitudinal slot in the bottom thereof for guiding the upward extending members of the winged structure and for admitting the projectile to the barrel with said projectile carrying the winged structure, a projector member reciprocable in the barrel, a spring 25 actuating said projector member with a reversion plunger handle at the back of the barrel, whereby said spring is tensioned, a stock for said gun and a supporting member whereby said barrel is carried on the stock and a trigger member pivoted in said supporting member for releasing the projector member and thereby discharging the projector carrying the winged structure.

THOMAS J. PARKER.
